(57) **CLAIM**

The ornamental design for a multi-slat architectural panel, as shown and described.

DESCRIPTION

FIG. 1 is a perspective view of a multi-slat architectural panel; FIG. 2 is a left elevational view thereof;

FIG. 3 is a right elevational view thereof;

FIG. 4 is a top plan view thereof;

FIG. 5 is a bottom plan view thereof; and,

FIG. 6 is a front elevational view thereof.

The broken lines included in the drawings are for illustrative purposes and form no part of the claimed design.
